(57) **CLAIM**

The ornamental design for a golf ball specific patch for a golf ball holder, as shown and described.

DESCRIPTION

FIG. 1 is a perspective view of the golf ball specific patch.

FIG. 2 is a front view of the golf ball specific patch.

FIG. 3 is a top view of the golf ball specific patch.

FIG. 4 is a left side view of the golf ball specific patch; and,

FIG. 5 is a right side view of the golf ball specific patch.

The broken line showing in FIGS. 1–5 is included for the purpose of illustrating conventional stitching that appears on the golf ball specific patch for a golf ball holder.

My golf ball specific patch is characterized by the smaller hole opening near the top and the larger hole opening near the bottom. The larger hole opening is also characterized by the slits on the left, right, and bottom.
